GEORGE T. PEARSONS, OF NEW YORK, N. Y., ASSIGNOR TO PYRENE MANUFACTURING COMPANY, OF NEW YORK, N. Y., A CORPORATION OF DELAWARE.

FIRE EXTINGUISHER.

Application filed November 7, 1916. Serial No. 129,931.

To all whom it may concern:

Be it known that I, GEORGE T. PEARSONS, a citizen of the United States, residing in the borough of Manhattan, in the city, county, and State of New York, have invented new and useful Improvements in Fire Extinguishers, of which the following is a specification.

This invention relates to fire extinguishers 10 of the syringe type in which a fire extinguishing liquid is discharged from a reservoir by a pumping mechanism upon each inward and outward movement of a reciprocable piston, and it is the object of the invention 15 to improve the general construction of extinguishers of this type to increase the efficiency thereof.

It is a further object of the invention 20 to provide a pumping mechanism having a piston chamber with suction inlets to opposite ends thereof connected with the reservoir and outlets from opposite ends connected to a discharge outlet to the exterior of the reservoir, a valve being operable to connect 25 the discharge outlet alternately with the outlets from opposite ends of the piston chamber by a piston reciprocable by a rod extending from the end of the piston chamber opposite to the discharge outlet.

Another object of the invention is to 30 provide the piston with means in a pumping mechanism of this character to co-operate with the discharge outlet when the piston is in its innermost position to close said outlet 35 to prevent leakage and evaporation of the contents of the reservoir through the discharge outlet.

A further object of the invention is to 40 provide means in a syringe with a pumping mechanism of this character to at all times connect the suction inlets of the pumping chamber with the liquid in the lowermost part of the reservoir in all positions of the syringe.

In the drawing accompanying and forming 45 a part of this specification Figure 1 is a sectional side elevation of a syringe showing an embodiment of my invention.

Figure 2 is a cross sectional view taken 50 substantially on the line 2—2 of Figure 1 and looking in the direction of the arrows; and

Figure 3 is a side elevation, partly in section, showing a modification of the intakes 55 to the piston chamber.

Similar characters of reference designate like parts throughout the different views of the drawing.

In carrying out the embodiment of the invention shown in the drawing, there is provided a reservoir comprising a tubular body portion 4 of rectangular shape in cross section and preferably of less width than height (Figure 2) to which body ends 5 and 6 are connected, one of said ends, shown as 60 the end 6, having a filler opening closed by a cap or plug 7 having a normally closed check valve opening into and closing outward from the reservoir.

A piston chamber is mounted in the reservoir adjacent the wall and which may constitute the top wall of the reservoir, said chamber comprising a cylinder 8 connected at opposite ends to heads 9 and 10 and by means of which heads the piston chamber 70 is supported in the reservoir. The head 9 has a part extending through an opening in the reservoir end with an outlet 11 to the exterior of the reservoir, and which outlet is in communication with opposite ends of 80 the piston chamber. Said head of the piston chamber is secured in place by soldering the projecting portion to the reservoir end. The opposite head has a bore of the same size as the bore of the cylinder and abuts against 85 the inner wall of the reservoir end 6 in line with an opening in the reservoir end of the same size as the bore in the head. This head is secured to the reservoir end 6 by a flanged nut 12 having screw threaded connection 90 with the head and clamped to the cylinder end 6 between the flange of the nut and said head.

A piston 13 having suitable packing is 95 reciprocable in the piston chamber by a rod 14, to one end of which the piston is secured, said rod extending through an opening in the nut 12 and packing 14' carried in a recess in said nut and which is in the nature of a stuffing box to the exterior of the reservoir and has an operating handle 14'' fixed thereto.

Each cylinder head 9, 10 has an inlet port 15, 16 to opposite ends of the piston chamber and to connect the piston chamber with the reservoir. Connected to the ports are tubes 17, 18 and the tubes connected by a coupling 19, which coupling is in the nature of a valve cage having valve seats 21, 22 and carrying valves, shown as ball valves 23, 24, 110

said valves being adapted to open into and close outward from the piston chamber, whereby as the piston is moved in one direction the suction of the piston will unseat 5 one of the valves and close the other, and when moved in the opposite direction closing the valve which was previously opened and opening the valve which was closed to alternately connect opposite ends of the 10 piston chamber with the reservoir.

To connect the outlet 11 to the piston chamber at opposite sides of the piston to discharge the liquid from opposite ends of the piston chamber, the cylinder head 10 has 15 a port 25 in a lateral extension 26 communicating with the piston chamber and the cylinder end 9 has a port 27 in a lateral extension 28, said port communicating with a chamber 29 in the cylinder head 9 with 20 which the outlet 11 communicates and is in the nature of an outlet to said chamber, said chamber constituting a compression chamber. Said chamber also has an inlet port 30 to connect the 25 chamber with the end of the piston chamber opposite to the port 25. The extensions extend in parallel directions toward the bottom of the reservoir, and the port 25 in the one extension is connected to the port 30 in the other extension and thereby connects the end of the piston chamber adjacent the operating handle with the compression chamber 29 by a pipe 31 extending parallel with the piston cylinder. To alternately shut off and open communication 35 between the compression chamber 29 and the piston chamber at opposite sides of the piston during the reciprocation of the latter there is provided a valve, shown as a ball 40 valve 32, located in the compression chamber adapted to co-operate with seats 33, 34 in the ports 27, 30 respectively. As the piston is moved in one direction or outward to draw liquid in front of the piston the 45 valve will be drawn to its seat in the port 30 discharging liquid from in back of the piston out through port 25, pipe 31 and port 27 into the compression chamber and from the latter through the outlet 11, and 50 when the piston is moved in the opposite direction the valve 32 will be seated in the port 27 and the liquid in front of the piston discharged through port 30 into the compression chamber and from the latter 55 through outlet 11.

To at all times connect the piston chamber with the liquid in the lowermost part of the reservoir in all positions of the syringe, intakes are connected to the suction inlets 15, 16 of the piston chamber, said intakes comprising tubes pivotally or rotatably supported in line with the longitudinal axis of the reservoir and to swing or revolve on an axis transverse to the longitudinal axis of the reservoir. These intakes

comprise two members or tubes 35, 36 secured to tubular members 37 rotatably mounted in bushings 41 in T-couplings 38 connected to one end of tubes 39, 40, which tubes are connected to the valve coupling 19 and the tubes 39, 40 through lateral ports 37' in said members. It will be noted that by this construction the tubes 35, 36 will lie adjacent opposite side walls of the reservoir, and being of a length to clear the top 75 and bottom walls, and the tubes 39, 40 being of such length that when the syringe is held in a vertical position the inlets to one or the other of the tubes 35, 36 will lie and be contiguous to the ends of the reservoir, according to which end of the reservoir is uppermost. The tubes of a pair of intakes rotate together with the members 37, and to provide a fluid-tight joint between the tubes and the bushings 41 washers 42 are interposed between the tubes and bushings. 80 To shut off communication between the tubes 35, 36 and the suction inlets to the piston chamber which are uppermost when the discharge end of the syringe is tilted upward from a horizontal position, and open communication between the lower tubes 35, 36 and the suction inlets, and vice versa, when the discharge end of the syringe is tilted downward from the horizontal, valve 95 mechanism is provided comprising a pair of valves 43, 44, carried within the coupling 38 adapted to co-operate with valve seats 45, 46 connected to or formed at the ends of the tubes 39, 40; said valves being in the form 100 of balls connected by a rod 47 extending through the tubes 39 and 40 and being of greater length than said tubes whereby when one valve is seated the other will be unseated. 105

To shut off communication between the tubes 36 and suction inlets 15, 16, and open communication between the tubes 35 and said suction inlets should the upper end of the reservoir be tilted to the left, as viewed 110 in Figure 2, or the syringe be held in a position with such side at the bottom, or to connect the tubes 36 with the suction inlets in the piston chamber and shut off communication between the tubes 35 and the 115 suction inlets should the reservoir be tilted to the right or with the side of the reservoir viewed at the right of Figure 2 at the bottom, valve mechanism is provided comprising a pair of valves 48 and 48' carried by 120 each of the tubular members 37 to co-operate with valve seats connected to or formed at opposite ends of said members, the valves being in the form of balls fixed to the ends of rods 49 extending through the tubular members 37 and being of greater length than said tubes whereby when one of the valves is seated the other will be unseated. 125

To prevent leakage and evaporation of the fire extinguishing liquid through the dis- 130

charge outlet 11 when the syringe is not in use and the piston is in its innermost position, valve mechanism is provided to co-operate with said outlet to close the same, 5 comprising a cork 50 slidably mounted in a tube 52 secured to the end of the piston opposite to the piston rod, the cork being urged outward to normally engage with an inwardly extending flange 53 of the tube by a 10 spring 54. This cork is adapted to co-operate with a tubular extension 55 of the discharge orifice 11 by the tube 52 extending through the outlet port 30 of the piston chamber; as clearly shown in Figure 1. To 15 lock the piston in its innermost position with the valve 50 closing the outlet 11, the piston rod adjacent the operating handle has a projection 56 which is adapted to pass through a slot in a cap 57 having threaded connection with the nut 12, and co-operate with 20 said cap by giving the piston a slight turn to retain the piston rod and piston in such position. It will be understood that the piston rod and piston may be readily released 25 by rotating the piston rod to cause the projection 56 to register with the slot in the cap. As soon as the projection is in register with 30 said slot the piston rod will be forced outward, due to the tension of the spring 54, against the tension of which spring the valve 50 is forced to seat the valve on the outlet extension 55.

In the modification shown in Figure 3 the construction of the syringe is substantially 35 similar to that shown in Figures 1 and 2 except that the intake tubes 35 and 36 instead of being supported to revolve may have an oscillatory movement whereby when 40 the syringe is in position with the pumping mechanism uppermost they will engage with the bottom of the reservoir and should the 45 syringe be inverted they will assume a position at opposite sides of the piston chamber, or may assume an intermediate position between the top and bottom of the reservoir. As the intake tubes are of metal, to prevent rattling of said tubes striking against the wall of the reservoir, they are provided 50 with buffers 58 of felt or the like at adjacent ends.

Having thus described my invention, I claim:

1. In a syringe the combination of a reservoir and a discharge outlet therefor at one 55 end; a piston chamber connected at opposite ends with the reservoir and having outlets from opposite ends; a chamber at one end of the piston chamber with which the reservoir outlet and the outlets of the piston chamber 60 are in communication; a piston; a piston rod to reciprocate the piston extending from the piston chamber at the end opposite to the other chamber; and a valve in the said other chamber operable during the reciprocation 65 of the piston to alternately connect the out-

lets of the piston chamber with said other chamber for the purpose specified.

2. In a syringe the combination of a reservoir; a piston chamber therein having suction inlets to opposite ends thereof; a piston 70 to reciprocate in the piston chamber; a casing at one end of the piston chamber having a chamber with an outlet to the exterior of the reservoir and a pair of inlet ports, one port communicating with one end of the piston chamber in axial alinement therewith and the other port connected to the opposite end of the piston chamber; and a ball valve in said chamber operable during the reciprocation of the piston to alternately shut off 75 and open up communication between said chamber and the piston chamber at opposite sides of the piston, substantially as and for the purpose specified.

3. In a syringe the combination of a reservoir having a discharge outlet; a piston chamber therein having suction inlets to connect the piston chamber at opposite ends with the reservoir; outlets from opposite ends of the piston chamber, one of said outlets being in the end of the piston chamber in line with the discharge outlet; a piston; a piston rod to one end of which the piston is connected and the opposite end extending from the piston chamber opposite to the discharge outlet; and means including a valve carried at the end of the piston opposite to the piston rod to pass through the outlet in the end of the piston chamber and close the discharge outlet when the piston is in its 100 innermost position, substantially as and for the purpose specified.

4. In a syringe the combination of a reservoir; a piston chamber therein having a casing at one end provided with a chamber having an outlet to the exterior of the reservoir and lengthwise of the piston chamber; a port to said casing chamber in line with the discharge outlet communicating with one end of the piston chamber; a second port to 105 said chamber connected to the opposite end of the piston chamber; suction inlets to connect opposite ends of the piston chamber with the reservoir; a piston; a rod to one end of which the piston is connected and the opposite end extending from the end of the piston chamber opposite to the discharge outlet; a valve in the casing chamber operable during the reciprocation of the piston to alternately shut off communication through 110 the ports thereto with opposite ends of the piston chamber; and means carried at the side of the piston opposite to the piston rod to pass through the port communicating with the one end of the piston chamber and 115 co-operate with the discharge outlet to close the same when the piston is in its innermost position, substantially as and for the purpose specified.

5. In a syringe the combination of a reser-

- voir having a discharge outlet in one end; a piston chamber therein having suction inlets to connect the piston chamber at opposite ends with the reservoir; means to connect 5 opposite ends of the piston chamber with the discharge outlet; a piston; a piston rod to one end of which the piston is connected and the opposite end extending from the piston chamber opposite to the discharge 10 outlet and having an operating handle connected thereto; a valve connected to the side of the piston opposite to the piston rod to close the discharge outlet when the piston is in its innermost position; and co-operating 15 locking parts carried by the piston rod and chamber adapted to co-operate to lock the piston in its innermost position, substantially as and for the purpose specified.
6. In a syringe the combination of a reservoir; a piston chamber in the reservoir at one side of the longitudinal axis of the reservoir; suction inlets to opposite ends of said chamber; means to connect the suction inlets with the liquid in the lowermost part 20 of the reservoir in all positions of the syringe; a chamber at one end of the piston chamber having an outlet to the exterior of the reservoir and co-axial with the piston chamber; a pair of ports to said chamber, one of said ports communicating with one 25 end of the piston chamber and being co-axial with the discharge outlet and the piston chamber; means to connect the other port with the opposite end of the reservoir; 30 a piston; a rod to one end of which the piston is connected with the other end extending from the piston chamber opposite to the discharge outlet; a valve in the chamber at the end of the piston chamber to co-operate with seats in the chamber ports during the reciprocation of the piston to alternately connect said chamber with the piston chamber at opposite sides of the piston; and a valve carried by the piston on the side 35 opposite to the piston rod adapted to pass through the port communicating and co-axial with the piston chamber and closing the discharge outlet, substantially as and for the purpose specified.
- 40 7. In a syringe the combination of a reservoir; a piston chamber located at the side of the reservoir having a suction inlet and an outlet to the exterior of the reservoir; a piston to reciprocate in said chamber; and an intake tube connected to the suction inlet supported to rotate on an axis transverse of the piston chamber and centrally of the reservoir and each end adapted to lie adjacent a side of the reservoir, substantially 45 as and for the purpose specified.
8. In a syringe the combination of a reservoir of rectangular shape in cross section; a piston chamber located adjacent the top of the reservoir having a suction inlet and an 50 outlet to the exterior of the reservoir; a piston to reciprocate in said chamber; and an intake tube connected to the suction inlet supported to swing on an axis transversely and centrally of the reservoir with both ends of the tube lying adjacent opposite sides and adapted to assume a position adjacent the top and bottom of the reservoir and intermediate the top and bottom, substantially as and for the purpose specified.
9. In a syringe the combination of a reservoir of rectangular shape in cross section; a piston chamber located in said reservoir having a suction inlet and an outlet to the exterior of the reservoir; a piston to reciprocate in said chamber; an intake tube connected to the suction inlet supported to swing on an axis transversely and centrally of the reservoir with both ends of the tube lying adjacent opposite sides and adapted to assume a position adjacent the top and bottom of the reservoir and intermediate the top and bottom, substantially as and for the purpose specified.
10. In a syringe the combination of a reservoir substantially rectangular in shape in cross section; a piston chamber in said reservoir with suction inlets to opposite ends thereof and an outlet from opposite ends to the exterior of the reservoir; a piston to reciprocate in said chamber; and a pair of intake tubes connected to the suction inlets supported to swing on an axis centrally and transversely of the reservoir with both ends lying adjacent opposite sides of the reservoir and adapted to assume a position either adjacent the top or bottom of the reservoir and positions intermediate the top and bottom, substantially as and for the purpose specified.
11. In a syringe the combination of a reservoir substantially rectangular in shape; a piston chamber in said reservoir with suction inlets to opposite ends thereof and an outlet from opposite ends of the piston chamber to the exterior of the reservoir; a piston to reciprocate in said chamber; a pair of intake tubes connected to the suction inlets supported to swing on an axis centrally and transversely of the reservoir with both ends lying adjacent opposite sides of the reservoir and adapted to assume a position either adjacent the top or bottom of the reservoir and positions intermediate the top and bottom; and valves to shut off communication between one end of each of the tubes and the suction inlets when the other end of said tubes is connected to the suction inlets, substantially as and for the purpose specified.
12. In a syringe the combination of a reservoir substantially rectangular in shape; a piston chamber in said reservoir with suc-

- tion inlets to opposite ends thereof and an outlet from opposite ends of the piston chamber to the exterior of the reservoir; a piston to reciprocate in said chamber; a pair of intake tubes connected to the suction inlets supported to swing on an axis centrally and transversely of the reservoir with both ends of the tube lying at opposite sides of the reservoir and adapted to assume a position either adjacent the top or bottom of the reservoir and positions intermediate the top and bottom; valves to shut off communication between one end of each of the intake tubes and the suction inlets when the other end of said tubes is connected to the suction inlets; and valves to shut off communication between one of the intake tubes and the suction inlets and connect the other tube thereto when the discharge end of the syringe is tilted upward from the horizontal, and shut off communication between one end of said intake tubes and connect the other tube thereto when the discharge end of the syringe is tilted downward from the horizontal, substantially as and for the purpose specified.
13. In a syringe the combination of a reservoir; a piston chamber therein having suction inlets to opposite ends thereof and arranged to connect the piston chamber with the liquid in the reservoir near the side and end which is lowermost in all positions of the syringe; a piston to reciprocate in the piston chamber; a casing at the inner end of the piston chamber having a chamber with an outlet to the exterior of the reservoir and a pair of inlet ports, one port communicating with one end of the piston chamber and the other port connected to the opposite end of the piston chamber; and a valve in said casing chamber operable during the reciprocation of the piston to alternately shut off and open up communication between said chamber and the piston chamber at opposite sides of the piston.
14. In a syringe the combination of a reservoir having a discharge outlet; a piston chamber therein; a piston to reciprocate in the piston chamber; means to control the entrance of liquid to and its discharge from the piston chamber at opposite sides of the piston during the reciprocation of the piston; means carried by the piston to engage with and close the discharge outlet when the piston is in its innermost position; and means to connect the opposite ends of the piston chamber with the liquid in the lowermost part of the reservoir in all positions of the syringe, substantially as and for the purpose specified.
15. In a syringe the combination of a reservoir having a discharge outlet; a piston chamber therein; a piston; a piston rod to one end of which the piston is connected and the opposite end extending from the piston chamber opposite to the discharge outlet; means to connect opposite ends of the piston chamber with the liquid in the lowermost part of the reservoir in all positions of the latter; means to control the entrance of liquid to and its discharge from the piston chamber at opposite sides of the piston; and a valve carried on the side of the piston opposite to the piston rod to engage with and close the discharge outlet when the piston is in its innermost position, substantially as and for the purpose specified.
16. In a syringe, the combination of a reservoir; a piston chamber in the reservoir; a piston to reciprocate therein; a casing with a chamber interposed between the inner end of the piston chamber and the end of the reservoir having an outlet opening to the exterior of the reservoir and a pair of inlet ports one of said ports being in communication with the piston chamber at one end of the piston and the other of said ports in communication with the piston chamber at the other end of the piston; valve mechanism in said chamber operative to control the discharge of liquid from the piston chamber into said casing chamber; suction inlet means to the piston chamber at opposite ends of the piston arranged to assume variable positions near the side and opposite ends of the reservoir; and means operable in said casing chamber by the piston when in an inner position to seat the same against and shut off the outlet from the casing chamber.
17. The combination with a reservoir, of a piston chamber; a piston in said chamber arranged with an operating rod extending from one end of the chamber to reciprocate the piston; a casing with a chamber at the end of the piston chamber opposite to the end from which the piston operating rod extends, said casing chamber having a discharge outlet and inlet ports, one of said inlet ports being in communication with the piston chamber at one end of the piston and the other of said inlet ports in communication with the piston chamber at the opposite end of the piston; valve mechanism in said chamber operative to control the discharge of liquid from the piston chamber into said casing chamber; inlet ports to the piston chamber at opposite ends of the piston and in communication with the reservoir; valve mechanism operable by the reciprocation of the piston to control the entrance of liquid from the reservoir to the piston chamber at opposite ends of the piston and the discharge of the liquid from the piston chamber at opposite ends of the piston into the casing chamber; and a valve operable in the casing chamber by the piston when in an inner position to be seated against and close the outlet from said chamber.

18. In a fire extinguisher, a liquid carrying reservoir, a pump including a cylinder and a piston to reciprocate therein having an operating handle projecting from one end of the cylinder, said cylinder being in communication with the liquid in the reservoir at opposite sides of the piston, means operative through the reciprocation of the piston to control the entrance of liquid from the reservoir to the piston cylinder, a chamber at the end of the piston cylinder oppo-
- site to that from which the piston operating rod projects having a discharge orifice and in communication with the piston cylinder at opposite sides of the piston, and means in said chamber operative through the action of the piston and of the liquid discharged from the piston cylinder to open communication between the piston cylinder and the discharge orifice. ¹⁵
